UNITED STATES PATENT OFFICE.

LENAR F. NELSON, OF RACINE, WISCONSIN.

GRINDSTONE.

Application filed June 3, 1920. Serial No. 386,247.

To all whom it may concern:

Be it known that I, LENAR F. NELSON, a citizen of the United States, and resident of Racine, in the county of Racine and State 5 of Wisconsin, have invented new and useful Improvements in Grindstones, of which the following is a description, reference being had to the accompanying drawings, which are a part of this specification.

10 The present invention relates to certain new and useful improvements in grindstones and refers more particularly to power driven grindstones.

It is one object of this invention to connect the driving power to the grindstone by means of a drive shaft substantially parallel with the grindstone supporting shaft and connected therewith by a drive connection whereby the direct pull upon the 20 grindstone shaft is eliminated.

Another object of the present invention is to provide an improved form of bearing member mounted about one side of the grindstone supporting frame for journaling 25 mounting the grindstone shaft and drive shaft.

A further object of this invention is to provide a grindstone driven as described and provided with means guarding the 30 drive connection between the drive shaft and the grindstone shaft.

A still further object of this invention is to provide a combined grindstone and emery wheel driven from one source of 35 power and so arranged that a person may use either the grindstone or the emery wheel without shifting his position.

With the above and other objects in view which will appear as the description proceeds, my invention resides in the novel construction, combination and arrangement of parts substantially as hereinafter described and more particularly defined by the appended claims, it being understood that such 45 changes in the precise embodiment of the herein disclosed invention may be made as come within the scope of the claims.

In the accompanying drawing I have illustrated one complete example of the physical embodiment of my invention constructed according to the best mode I have so far devised for the practical application of the principles thereof, and in which:

50 Figure 1 is a side view of a grindstone and emery wheel embodying the features of my invention;

Figure 2 is a top plan view thereof; and Figure 3 is a view part in section and part in elevation taken therethrough on the plane of the line 3—3 of Figure 1.

Referring now more particularly to the accompanying drawing, the numeral 5 designates a supporting frame, preferably formed by a rectangular top portion 6 of channel iron having supporting legs 7 of angle iron connected therewith, and braced as at 8.

Secured centrally on the top of one longitudinal channel iron 6 is a bearing member 9 in which one end of a grindstone shaft 10 is journaled, the other end of the shaft being journaled in a double bearing 11 which is cut away or recessed as at 12 to receive the other longitudinal channel iron 6. The bearing member 11 is secured in place by bolts or other fastenings 13 which pass through the side projections 14 and 15 of the upper and lower portions of the bearing member and the adjacent channel iron 6.

Mounted within the space formed by the rectangular framework 6 and carried by the shaft 10 is a grindstone 16, and as usual in constructions of this character, the stone may be turned by a hand crank 17 detachably connected to one square end of the shaft 9, but in the present instance the wheel is designed to more especially be rotated by power means (not shown) with which a drive belt 18 is connected.

The drive belt 18 is trained about a pulley 19 fixed to the outer end of a drive shaft 20 journaled in the portion 21 of the bearing 11, and this shaft is connected with the shaft 10 by a relatively small gear 22 fixed to the inner end thereof and meshed with a relatively large gear 23 fixed to the shaft 10. The gear connection between the shafts 10 and 20 is protected by a housing 24 which may be either cast integral with the bearing 11 or independent thereof, and as will be readily understood, the ratio between the gears 22 and 23 is such as to best adapt the same to the power means with which it may be connected.

As oftentimes it is convenient to have an emery wheel positioned where an operator can use the grindstone and emery wheel alternately, I provide a small supplemental frame 25 secured to the channel iron 6 to which the bearing 11 is connected, the frame being held in place by fastenings 26. Formed

integral with the frame 25 is a bearing member 27 in axial alinement with a bearing member 28 secured to the adjacent channel iron 6, and journaled in said bearing members is an emery wheel supporting shaft 29 on which is mounted an emery wheel 30 disposed between the supplemental frame and main frame.

10 The emery wheel 30 is driven from the same source of power as the grindstone and has a pulley 31 secured to an end of shaft 29 projected beyond the bearing 27 in line with a relatively large pulley 32 fixed to the shaft 20, the pulleys 31 and 32 being driv-
15 ingly connected by a belt 33. The supplemental frame 25 is provided with some form of tool rest 34 and the ratio between the pulleys 31 and 32 provides the proper speed for the emery wheel.

20 The grindstone runs in a trough or pan 35 adapted to retain water or other similar fluid. As will be readily obvious, I provide a combined grindstone and emery wheel which will perform their functions in a
25 highly efficient manner.

What I claim as my invention is:

1. In combination, a supporting frame including a pair of spaced longitudinally ex-

tending members, a bracket secured to one of said members and having two bearings, a bearing associated with the other of said members, a grindstone supporting shaft one end of which is journaled in one of the first mentioned bearings and the other end of which is journaled in the last mentioned bearing, a drive shaft journaled in the other of the first mentioned bearings, and means operatively connecting said shafts.

2. In combination, a supporting frame including a pair of spaced longitudinally extending members, a bracket secured to one of said members and having two bearings, a bearing associated with the other of said members, a grindstone supporting shaft one end of which is journaled in one of the first mentioned bearings and the other end of which is journaled in the last mentioned bearing, a drive shaft journaled in the other of the first mentioned bearings, gears operatively connecting said shafts, and a housing member carried by said bracket and adapted to enclose said gears.

In testimony whereof, I affix my signature.

IENAR F. NELSON.
